DESIGN FOR A HAND BAG

Kiriakos Kichu and Stephen Marino,
Haverhill, Mass.

Application March 19, 1935, Serial No. 55,954

Term of patent 7 years

To all whom it may concern:

Be it known that we, Kiriakos Kichu and Stephen Marino, both citizens of the United States, residing at Haverhill, in the county of Essex and State of Massachusetts, have invented a new, original, and ornamental Design for Hand Bag, of which the following is a specification, reference being had to the accompanying drawing, forming part thereof.

Figures 1 and 2 are opposite side elevational views of a hand bag showing our new design.

Figures 3 and 4 are opposite edge elevational views of the same.

The principal and dominating feature of our design consists in the circular concentric rows of lacing of contrasting color in the sides of the bag, as well as the two parallel rows of similar lacing of contrasting color in the edge of the bag and also the single row of similar lacing of contrasting color in the central portion of the handle of the bag, substantially as shown.

We claim:

The ornamental design for a hand bag as shown and described.

KIRIAKOS KICHU.
STEPHEN MARINO.
